(57) **CLAIM**

The ornamental design for a can rack, as shown and described.

DESCRIPTION

FIG. 1 is a front perspective view of a can rack, showing my new design.

FIG. 2 is a rear perspective view thereof;

FIG. 3 is a front elevational view thereof;

FIG. 4 is a rear elevational view thereof;

FIG. 5 is a left side view thereof, the right side view being a mirror image of FIG. 5; and,

FIG. 6 is a top plan view thereof, the bottom plan view being a mirror image of FIG. 6.

The dashed broken lines in the figures are for the purposes of illustrating portions of the can rack, which form no part of the claimed design.

1 Claim, 6 Drawing Sheets
